COMBINATION CAP AND SCREW DRIVER FOR CONTAINER OF LIGHTER FLUID

Charles A. Byrne, Washington, D. C.

Application January 4, 1956, Serial No. 39,598

Term of patent 14 years

(Cl. D58—26)

FIG. 1

FIG. 2

FIG. 3

FIG. 4

Fig. 1 is a front elevational view of a combination cap and screw driver for container of lighter fluid embodying my new design;

Fig. 2 is a side elevational view thereof;

Fig. 3 is a top plan view thereof; and

Fig. 4 is a horizontal sectional view taken on the line 4-4 of Fig. 1, looking in the direction of the arrows and taken near the base of the cap.

I claim:

The ornamental design for a combination cap and screw driver for a container of lighter fluid, as shown.
